(57) **CLAIM**

The ornamental design for eyeblack glass frames, as shown and described.

DESCRIPTION

FIG. 1 is a perspective view of an ornamental design of eyeblack glass frames showing my new design.

FIG. 2 is a front elevational view thereof.

FIG. 3 is a right side elevational view thereof.

FIG. 4 is a rear elevational view thereof.

FIG. 5 is a top plan view thereof.

FIG. 6 is a bottom plan view thereof; and,

FIG. 7 is a left side elevational view thereof.

The broken lines in FIGS. 1-7 represent environmental subject matter and form no part of the claimed design.

1 Claim, 4 Drawing Sheets

FIG. 2

FIG. 3

FIG. 4

FIG. 5

FIG. 6
